UNITED STATES PATENT OFFICE

2,134,260

AEROPLANE CONSTRUCTION

James H. Nickerson, Kansas City, Kans.

Application September 7, 1935, Serial No. 39,564

1 Claim. (Cl. 244—119)

This invention relates to aircraft construction and particularly the body thereof and the primary object is the provision of unique and novel means for producing a strong and desirable body 5 wherein the covering thereof is tensioned in such fashion as to establish a self-supporting, self-trussed body with longitudinally extending members which further contribute to the rigidity and strength of the unitary body of the aircraft.

10 One of the important aims of this invention is to provide an aeroplane body wherein is included a plurality of longitudinally extending sheets that form a cover for the frame of the body and which are joined along their proximal longitudinal edges in such fashion as to produce a tension within the sheets so joined and whereby a longitudinal structural member is created along the length of the body for the purpose of further strengthening, bracing and rendering unitary, the body.

15 Other objects of the invention include specific means whereby the aforementioned broad general objects are incorporated in an aircraft body structure and such minor objects will appear during the course of the following specification referring 20 to the accompanying drawing, wherein:

Figure 1 is a perspective view of an aeroplane body made in accordance with the present invention.

Fig. 2 is an enlarged, cross sectional view 25 through the same.

Fig. 3 is a greatly enlarged, fragmentary, detailed, sectional view through one of the joints of the body.

Fig. 4 is a fragmentary, detailed, cross-sectional 30 view through a portion of the body wall taken on line IV—IV of Fig. 3.

Fig. 5 is a fragmentary, detailed, sectional view 35 through the body wall and illustrating the manner in which the covering may be attached to one of the bulkheads.

Fig. 6 is a fragmentary, sectional view similar 40 to Fig. 3, but illustrating the manner in which the flanges of the sheets forming the covering for the body frame may be turned inwardly.

Fig. 7 is a similar view to that illustrated in 45 Fig. 6 with the flanges of the covering sheets projecting outwardly, and

Fig. 8 is a cross-sectional view through an 50 aeroplane body embodying a modified type of bulkhead and which is made to impart pressure between bulkhead and covering and tension to the said covering.

It is well known in this art that aeroplane body 55 construction must be such that the racking and twisting imparted thereto when in use, is over-

come and weaknesses which have been generally encountered are to a large extent due to the weakness of the frame per se and since it is common practice to hang the covering of an aeroplane body directly upon the frame, this covering does not contribute to strengthening the frame nor to lending rigidity or strength to the entire unitary body itself. Ordinarily, tensioning tie members are stretched between the various structural units of the frame of an aeroplane body 10 and these tie members customarily have means for drawing the units of the frame together or establishing a relation there-between which contributes to a desired end.

Tensioning of the covering has heretofore not 15 entered into the solution of the structural problem and it is the purpose of this invention to provide such a covering for an aeroplane body and to gain a complete understanding of the principles involved reference may be had to the accompanying drawing, wherein are illustrated several 20 embodiments of the invention. In creating the aeroplane body, a frame is always provided and in this instance, the same comprises a plurality of bulkheads 10 each of which is in the form of 25 a ring or annulus that is circumscribed by the covering 12 of the body. This covering comprises a number of longitudinally extending sheets 14 formed intermediate their ends to permit obtaining the desired contour and each having laterally extending flange 16 which terminates in a 30 rebent margin 18 as clearly illustrated in Figs. 3 and 7.

The longitudinal edges of each sheet 14 therefore, present a substantially U-shaped cross-sectional outline and a longitudinally extending strip 20 is positioned at the base of this attenuated U-shaped marginal portion along each longitudinal edge of each sheet respectively. The edges of the several sheets forming the complete 40 covering for the body are spaced apart as illustrated and means is provided for securing together these proximal edges. This means may be in the form of a conventional type bolt and nut 22 and 24 respectively and the bolt passes 45 through apertures formed through flanges 16 and longitudinal strips 20. In the event some resiliency is desired between the securing means and the joint structure just described, a specially formed washer 26 such as illustrated in Fig. 7 50 may be interposed between one of strips 20 and the nut 24.

In the preferred embodiment of the invention which is illustrated in Figs. 1, 2, 3, 4, and 7, the proximal edges of sheets 14 are a distance apart 55

which positively insures that no abutment takes place and the combined peripheral dimension of the bulkhead 10 along the line of contact with covering 12 is greater than the combined widths 5 of all of sheets 14 at that line. Therefore, upon tightening the securing members in the form of bolts 22, a tension is established within each and every one of the sheets 14 and a pressure is exerted against the outer periphery of the adj-10 cent bulkhead 10. In most instances it is desired to cover the longitudinally extending joint structure which has been described and as illustrated in Figs. 1 and 3, a transversely arched spanner 15 28 is provided and secured to adjacent sheets 14 in the manner shown. This spanner is resilient enough to be moved to position so that screws or analogous means 30 may secure it to the under-20 lying sheets 14. In the form of the joint structure shown in Fig. 6 the flanges 16 are turned inwardly and a notch 32 provided in the under-25 lying bulkhead 10 allows free passage of this longitudinally extending joint. The space between proximal sheets 14 in this particular type of construction is bridged by a spanner 34 which lies in a plane parallel to the normal plane of sheets 14. While it is not contemplated that the covering be attached to the several bulkheads, reference to Fig. 5 will readily illustrate that such can be done and in such event, rivets 36 will ex-30 tend from bulkhead 10 through a slot 38 so that while rivet 36 holds the covering to the bulkhead relative movement between the said elements may take place when the aeroplane body is subject to racking.

35 In Fig. 8, the invention is embodied in the form of an expandable bulkhead 50 about which is wrapped a covering 52. The tensioning of cover-

ing 52 and the setting up of a pressure between bulkhead and covering 50 and 52 respectively, is accomplished by the expander member 54 which is in screw-threaded engagement with the ends of the split bulkhead 50. Right and left hand screw-threads on member 54 and in the openings which receive the ends of member 54, insure that the turning of said member will increase and decrease the peripheral dimension of bulkhead 50. Obviously tensioning of covering 52 will take 10 place when the bulkhead is expanded.

While several forms of the invention have been illustrated and described, it is understood that a large number of structural modifications and changes might be made without departing from 15 the spirit of the invention and scope of the appended claim.

Having thus described the invention, what is claimed as new and desired to be secured by Letters Patent is:

An aeroplane body comprising a frame; a covering of longitudinally extending rigid sheets of metal having their proximal edges spaced apart; laterally extending, radially disposed flanges formed along the said edges of the sheets 25 and having rebent margins extending throughout their lengths; means for joining the flanged edges of said sheets to produce a tension within the sheets of the covering and a pressure against the said frame; and spanners bridging the joint 30 formed by the adjacent edges of adjoining sheets, said flanges of the sheets extending outwardly from the body and said spanner bridging the joint being arcuate in cross section and contacting said rebent margins whereby to house the 35 said flanges and joining means therebeneath.

JAMES H. NICKERSON.
